US0D1109126S

(12) **United States Design Patent** (10) Patent No.: **US D1,109,126 S**
(45) Date of Patent: ** Jan. 13, 2026

(54) **HEADPHONE**

(71) Applicant: **SHENZHEN SHOKZ CO., LTD.**,
Shenzhen (CN)

(72) Inventors: **Lei Zhong**, Guangdong (CN); **Sunjie Huang**, Guangdong (CN); **Zeteng Yan**, Guangdong (CN); **Haochen Liu**, Guangdong (CN); **Shuailin Xie**, Guangdong (CN)

(73) Assignee: **SHENZHEN SHOKZ CO., LTD.**,
Shenzhen (CN)

(**) Term: **15 Years**

(21) Appl. No.: **35/522,477**

(22) Filed: **Sep. 22, 2023**

(80) **Hague Agreement Data**

Int. Filing Date: **Sep. 22, 2023**

Int. Reg. No.: **DM/232178**

Int. Reg. Date: **Sep. 22, 2023**

Int. Reg. Pub. Date: **Sep. 27, 2024**

(30) **Foreign Application Priority Data**

Apr. 23, 2023 (CN) 202330228921.3

Aug. 11, 2023 (CN) 202330514251.1

(51) LOC (15) Cl. **14-01**

(52) U.S. Cl.

USPC **D14/205**

(58) **Field of Classification Search**
USPC D14/205, 188, 192; 381/380-381
